TACKING LATCH FOR STAPLING
MACHINESElliott J. Lash, Seaford, N.Y., assignor to Ace Fastener
Corporation, Chicago, Ill., a corporation of Illinois
Filed Feb. 10, 1960, Ser. No. 7,809
7 Claims. (Cl. 1-3)

This invention relates to a tacking latch for stapling machines which have a base and a magazine pivotally connected to the base. The tacking latch permits the magazine to be connected to the base for stapling but permits the base to be swung away from the magazine by actuating the latch when it is desired to utilize the machine as a tacker.

It is preferable, in tacking latch constructions, to require the latch to be released manually to swing the base away from the magazine. The releasing action should be consciously performed by the operator to prevent releasing of the base from the magazine when tacking is not desired.

The tacking latch of the instant invention carries out the functions of such device in an efficient and workmanlike manner. The latch is easily applied to stapling machines and is simple, foolproof, and relatively inexpensive to manufacture.

The instant invention may be briefly described as comprising, in a stapling machine having a base and a magazine pivotally connected to the base, the improvement of a support member upon the base having engaging means thereupon, a latching member upon the magazine having complementary engaging means thereupon, and means for engaging and disengaging the support member from the latching member.

In the specific modification of this invention, as set forth in the drawings, a rail is provided within the magazine having a pair of spaced upstanding portions and a base thereupon. The base of the rail is secured to the interior face of the base of the magazine. A pair of spaced openings are provided at the base of the magazine which register with an additional pair of spaced openings provided at the base of the rail. The support member is bifurcated and is at least partially disposable within the said openings. A guide rod is provided within the magazine, a follower is disposed upon the guide rod, and a spring is provided between the follower and the latching member.

The specific form of the invention also contains some additional constructional features as are set forth in some of the limited claims in this case. The above description, however, sets forth the principal features of such specific modification.

Various other objects and advantages of this invention will become apparent as the description herein proceeds.

The invention will now be further described by reference to the accompanying drawings which are made a part of this specification.

FIG. 1 is a fragmentary side view of a stapling machine embodying the tacking latch of this invention.

FIG. 2 is a sectional view of the stapling machine shown in FIG. 1 taken along lines 2-2 of FIG. 1.

FIG. 3 is a sectional view of the stapling machine shown in FIG. 2 taken along lines 3-3 of FIG. 2.

FIG. 4 is a rear view of a stapling machine, including the tacking latch of this invention, with the word "press" shown upon the handle portion of the latching member of the device so as to illustrate the direction of movement of the latch.

FIG. 5 is a detailed perspective view, partly in section, of the latching member and associated parts of the tacking latch of this invention.

2

FIG. 6 is a sectional view through the stapling machine shown in FIG. 2 taken along lines 6-6 of FIG. 2.

FIG. 7 is a fragmentary plan bottom view in open tacking position of the stapling machine having the tacking latch of this invention.

FIG. 8 is an enlarged sectional view of the form of the invention shown in FIG. 3 taken along lines 8-8 of FIG. 3.

FIG. 9 is a sectional view along lines 9-9 of FIG. 8. Referring to the drawings for a detailed description of this invention, the stapling machine 11 is formed with a base 12, a hanger 13 upon said base, which is formed with a pair of upstanding portions 13a, an anvil 14 upon said base and a magazine 15 pivotally connected by hinge-pin 16 between the upstanding portions 13a of hanger 13.

Anvil 14 is movable upon base 12 and is secured in two specific positions by downwardly depending members 17 and spring 18.

Base 12 also bears supporting feet 19 which are secured into position by rivets 20.

A bottom cover 21 is secured to base 12 by tongue portion 22 disposed above front foot 19 and by springable portions 23.

A bottom portion 25 joins the two sides of hanger 13 to one another and is secured to the underside of base 12 by rivets 26.

A recess 27 is provided within base member 12 and a springable lower support member 28 disposed within said recess and secured into position by portion 27 of hanger 13. A support member 29, having a pair of bifurcated portions 29a, is movably retained within a recess in base 12. Each of portions 29a are formed with hook portions 30 at their upper ends. An upper support member 31 integral with bifurcated portions 29a joins each of members 29a to one another and also retains spring 32 therewithin.

In the preferred modification of this invention, although not necessary for the operation thereof, recess 27 within base 12 is larger than support member 29 so that support member 29 is pivotally movable with respect to base member 12, thereby producing smoother engagement of the portions of the tacking latch of this invention.

Magazine 15 is equipped with rail 33 which is formed with a base portion 34 and lateral upstanding spaced portions 35.

Rail 33 bears a front upstanding portion 37 and a rear upstanding portion 38. Front upstanding portion 37 is provided with hole 39 therewithin and rear upstanding portion 38 is provided with hole 40 therewithin. Follower guide rod 41 is disposed within holes 39 and 40 and is secured into position upon magazine 15 by snap ring 42.

Follower 43 is slidably disposed upon follower guide rod 41 by means of an opening 44 within follower 43. A follower retracting member 45 is secured to follower 43 by rivet 46.

The base 47 of magazine 15 is provided with spaced openings 48 and the base 34 of rail 33 are provided with additional spaced openings 49 which register with openings 48. Support member 29 is at least partially disposable within the openings 48-49.

A latching member 50 is formed with a base portion 51 which is adapted to lie along the inner face 52 of rail 33 and is partially disposable within recesses 36 within upstanding portions 35 of rail 33.

65 A coil spring 53 is disposable upon guide rod 41 between follower 43 and latching member 51 and normally tends to push follower 43 forwardly and latching member 51 rearwardly.

Latching member 51 also bears a handle portion 57 which is offset from its base portion 51 and is partially disposed within an opening 58 in the rear of magazine 15. Handle portion 57 is further disposed over hinge-

pin 16 and bears an additional offset actuating portion 59 at the rear thereof. Handle portion 57 is also provided with an opening 62 therewithin.

Base portion 51 of latching member 50 is further provided with an additional pair of openings 60 which are adapted to abut hook portions 30 of support member 29. A portion 61 of base portion 51 is disposed forward of openings 60.

With the foregoing specific description of the parts of the invention the operation thereof will now be explained.

The stapling machine embodying the tacking latch of this invention is first assumed to be in stapling position with the tacking latch engaged. In this position spring 53 pushes follower 43 forwardly and latching member 50 rearwardly. The forward part of base portion 51 is also held against upward displacement by recesses 36.

As can be seen in the drawings, when latching member 50 is in the above position openings 60 are out of registration with openings 48-49. Hook portions 30 of support member 29 are thus held in engaged position by portion 61 of latching member 50.

Thus, in this position, while magazine 15 can move downwardly against anvil 14 for stapling action, magazine 15 can not move above the engagement point of hook portions 30 with latching member 50.

If tacking is now desired so that base 12 is to be swung away from magazine 15, all the operator need do is to push actuating portion 59 in the "press" direction as shown in FIG. 4. This pressure moves latching member 50 forwardly against the pressure of spring 53. The forward movement is stopped by the abutment of actuating portion 57 against the rear of magazine 15. This movement causes openings 60 to register with openings 48-49 and thus permits hook portions 30 to be removed from their engaged position. The base 12 can now be swung away from magazine 15 for tacking.

When tacking has been completed and the stapling machine is to be placed in stapling position, all that need be done is to swing base 12 and magazine 15 into normal alignment. Hook portions 30 then enter openings 48-49 and then bear against portion 61 of latching member 50. The force exerted upon portion 61 forces it forwardly against the pressure of spring 53 thus causing hook portions 30 to enter openings 60. Once hook portions 30 enter openings 60 spring 53 pushes latching member 50 rearwardly and thus lock the parts into position.

Where support member 29 is made pivotally movable, the engagement of the parts is facilitated by the simultaneous pivotal movement of support member 29 with the forward movement of portion 61 so that smoother engagement of the parts is accomplished.

The parts are assembled to one another by taking the completed assembly of magazine 15 and rail 33 and thence taking guide rod 41 and disposing snap ring 42 thereupon outside and rearward of the recess (not shown) therewithin. Guide rod 41 is then inserted into hole 39 in front upstanding portion 37 and pushed forward as far as it will go. Follower 43 is slidably placed upon guide rod 41 and spring 53 disposed behind follower 43. Base portion 51 of latching member 50 is pushed through opening 58 (the sides of magazine 15 can be pushed apart somewhat to ease the assembly if necessary) and the most forward portion of base portion 51 of latching member 50 disposed within recesses 36 within rail 33.

Guide rod 41 is then inserted into hole 62 within handle portion 57 and thence into hole 40 in rear upstanding portion 38 and pushed back as far as it will go. Snap ring 42 is then disposed into the recess (not shown) within guide rod 41 so as to hold the parts in place.

Magazine 15 is then placed between upstanding portions 13a of hanger 13 and hinge-pin 16 driven into the

aligned openings within portions 13a and magazine 15 so as to secure the parts into position.

The foregoing specific embodiments of this invention as set forth in the specification herein are for illustrative purposes and for purposes of example only.

Various changes and modifications can obviously be made within the spirit and scope of this invention and would occur to those skilled in this art.

I claim:

10. In a stapling machine having a base, a magazine pivotally connected to said base, a follower guide rod within said magazine, and a follower movable along said follower guide rod, the improvement which comprises a pair of spaced openings at the base of said magazine, a bifurcated support member upon said base extending upwardly therefrom, each bifurcation of said support member extending through said openings at the base of said magazine and having engaging means at the ends thereof; an axially movable latching member at one end of said magazine having a pair of spaced openings therein registering with said magazine openings, and a coil spring disposed upon said follower guide rod between said latching member and said follower, said coil spring urging said latching member into latched engagement with said engaging means.
15. In a stapling machine having a base, a magazine pivotally connected to said base, a follower guide rod within said magazine, and a follower movable along said follower guide rod, the improvement which comprises a pair of spaced openings at the base of said magazine, a bifurcated support member upon said base extending upwardly therefrom, each bifurcation of said support member extending through said openings at the base of said magazine and having engaging means at the ends thereof; an axially movable latching member at one end of said magazine having a pair of openings therein registering with said magazine openings, a coil spring disposed upon said follower guide rod between said latching member and said follower, and an additional spring connected to said support member, said coil spring normally urging said latching member into latched engagement with said engaging means.
20. In a stapling machine having a base, a magazine pivotally connected to said base, a follower guide rod within said magazine, and a follower movable along said follower guide rod, the improvement which comprises a pair of spaced openings at the base of said magazine, a bifurcated support member upon said base extending upwardly therefrom, each bifurcation of said support member extending through said openings at the base of said magazine and having engaging means at the ends thereof; an axially movable latching member at one end of said magazine having a pair of openings therein registering with said magazine openings, a coil spring disposed upon said follower guide rod between said latching member and said follower, and an additional spring connected to said support member, said coil spring normally urging said latching member into latched engagement with said engaging means.
25. In a stapling machine having a base, a magazine pivotally connected to said base, a follower guide rod within said magazine, and a follower movable along said follower guide rod, the improvement which comprises a pair of spaced openings at the base of said magazine, a bifurcated support member upon said base extending upwardly therefrom, each bifurcation of said support member extending through said openings at the base of said magazine and having engaging means at the ends thereof; an axially movable latching member at one end of said magazine having a pair of openings therein registering with said magazine openings, a coil spring disposed upon said follower guide rod between said latching member and said follower, and an additional spring connected to said support member, said coil spring normally urging said latching member into latched engagement with said engaging means.
30. In a stapling machine having a base, a magazine pivotally connected to said base, a rail within said magazine, and a follower axially movable within said magazine, the improvement which comprises an opening at the base of said magazine, a support member upon said base extending upwardly therefrom having engaging means at the end thereof, said support member extending through said opening at the base of said magazine, an additional opening at the rear of said magazine, an axially movable latching member having a base portion adapted to lie along the inner face of the base of said magazine and an offset handle portion adapted to be at least partially disposed within said additional opening, said lower portion of said latching member also having second engaging means thereupon registering with and complementary to said first engaging means upon said support member, and spring means disposed between said offset portion of said latching member and said follower.
35. In a stapling machine having a base, a magazine pivotally connected to said base, a rail within said magazine, and a follower axially movable within said magazine, the improvement which comprises an opening at the base of said magazine, a support member upon said base extending upwardly therefrom having engaging means at the end thereof, said support member extending through said opening at the base of said magazine, an additional opening at the rear of said magazine, an axially movable latching member having a base portion adapted to lie along the inner face of the base of said magazine and an offset handle portion adapted to be at least partially disposed within said additional opening, said
40. In a stapling machine having a base, a magazine pivotally connected to said base, a rail within said magazine, and a follower axially movable within said magazine, the improvement which comprises an opening at the base of said magazine, a support member upon said base extending upwardly therefrom having engaging means at the end thereof, said support member extending through said opening at the base of said magazine, an additional opening at the rear of said magazine, an axially movable latching member having a base portion adapted to lie along the inner face of the base of said magazine and an offset handle portion adapted to be at least partially disposed within said additional opening, said
45. In a stapling machine having a base, a magazine pivotally connected to said base, a rail within said magazine, and a follower axially movable within said magazine, the improvement which comprises an opening at the base of said magazine, a support member upon said base extending upwardly therefrom having engaging means at the end thereof, said support member extending through said opening at the base of said magazine, an additional opening at the rear of said magazine, an axially movable latching member having a base portion adapted to lie along the inner face of the base of said magazine and an offset handle portion adapted to be at least partially disposed within said additional opening, said
50. In a stapling machine having a base, a magazine pivotally connected to said base, a rail within said magazine, and a follower axially movable within said magazine, the improvement which comprises an opening at the base of said magazine, a support member upon said base extending upwardly therefrom having engaging means at the end thereof, said support member extending through said opening at the base of said magazine, an additional opening at the rear of said magazine, an axially movable latching member having a base portion adapted to lie along the inner face of the base of said magazine and an offset handle portion adapted to be at least partially disposed within said additional opening, said
55. In a stapling machine having a base, a magazine pivotally connected to said base, a rail within said magazine, and a follower axially movable within said magazine, the improvement which comprises an opening at the base of said magazine, a support member upon said base extending upwardly therefrom having engaging means at the end thereof, said support member extending through said opening at the base of said magazine, an additional opening at the rear of said magazine, an axially movable latching member having a base portion adapted to lie along the inner face of the base of said magazine and an offset handle portion adapted to be at least partially disposed within said additional opening, said
60. In a stapling machine having a base, a magazine pivotally connected to said base, a rail within said magazine, and a follower axially movable within said magazine, the improvement which comprises an opening at the base of said magazine, a support member upon said base extending upwardly therefrom having engaging means at the end thereof, said support member extending through said opening at the base of said magazine, an additional opening at the rear of said magazine, an axially movable latching member having a base portion adapted to lie along the inner face of the base of said magazine and an offset handle portion adapted to be at least partially disposed within said additional opening, said
65. In a stapling machine having a base, a magazine pivotally connected to said base, a rail within said magazine, and a follower axially movable within said magazine, the improvement which comprises an opening at the base of said magazine, a support member upon said base extending upwardly therefrom having engaging means at the end thereof, said support member extending through said opening at the base of said magazine, an additional opening at the rear of said magazine, an axially movable latching member having a base portion adapted to lie along the inner face of the base of said magazine and an offset handle portion adapted to be at least partially disposed within said additional opening, said
70. In a stapling machine having a base, a magazine pivotally connected to said base, a rail within said magazine, and a follower axially movable within said magazine, the improvement which comprises an opening at the base of said magazine, a support member upon said base extending upwardly therefrom having engaging means at the end thereof, said support member extending through said opening at the base of said magazine, an additional opening at the rear of said magazine, an axially movable latching member having a base portion adapted to lie along the inner face of the base of said magazine and an offset handle portion adapted to be at least partially disposed within said additional opening, said
75. In a stapling machine having a base, a magazine pivotally connected to said base, a rail within said magazine, and a follower axially movable within said magazine, the improvement which comprises an opening at the base of said magazine, a support member upon said base extending upwardly therefrom having engaging means at the end thereof, said support member extending through said opening at the base of said magazine, an additional opening at the rear of said magazine, an axially movable latching member having a base portion adapted to lie along the inner face of the base of said magazine and an offset handle portion adapted to be at least partially disposed within said additional opening, said

lower portion of said latching member also having second engaging means thereupon registering with and complementary to said first engaging means on said support member, and spring means disposed between said offset portion of said latching member and said follower.

5. In a stapling machine having a base, a magazine having a base portion and pivotally connected to the base of said machine, a rail within said magazine having a pair of spaced upstanding portions and a base portion thereupon, a follower and a follower guide rod connected to said rail, said follower being slidable on said follower guide rod, the improvement which comprises a pair of spaced first openings at the base of said magazine and a pair of spaced second openings at the base of said rail in registration therewith, an upwardly extending pivotally movable bifurcated support member upon said base having hooked portions at the upper part of each of said bifurcations, each bifurcation being partially disposable within said first and second openings, a spring member upon said support member, an additional opening at the rear of said magazine, an axially movable latching member having a base portion extending along the inner face of the base of said magazine and an offset handle portion partially disposed within said additional opening, said base portion of said latching member also having a pair of spaced recesses engageable with said hooked members, said offset portion of said latching member being also provided with an opening therewithin to accommodate one end of said guide rod, and coil spring means disposed between said latching member and said follower urging said latching member into latched engagement with said hooked portion of said support member.

6. In a stapling machine having a base, a magazine having a base portion and pivotally connected to the base of said machine, a rail within said magazine having a pair of spaced upstanding portions and a base portion thereupon, a follower guide rod connected to said rail, and a follower connected to and movable along said follower guide rod, the improvement which comprises a slot within each of the upstanding portions of said rail, a pair of spaced first openings at the base of said magazine and a pair of spaced second openings at the base of said rail in registration therewith, an upwardly extending pivotally movable bifurcated support member upon said base having engaging portions thereupon, each bifurcation of said support member extending through said first and second openings; a first spring member upon said support member, an additional opening at the rear of said magazine, an axially movable latching member having a base portion extending along the inner face of the base of said magazine, a second spring member upon said latching member, and a base portion of said latching member being received within said additional opening.

zine, said base portion partially disposed within the slots in the upstanding portions of said rail, and an offset handle portion partially disposed within said additional opening, said base portion of said latching member also having complementary engaging means thereupon, said offset portion of said latching member being also provided with an opening therewithin to accommodate one end of said guide rod, and coil spring means disposed between said latching member and said follower urging said latching member into latched engagement with said engaging portion.

7. In a stapling machine having a base, a magazine having a base portion pivotally connected to the base of said machine, a rail within said magazine having a pair of spaced upstanding portions and a base thereupon, a follower guide rod connected to said rail and a follower connected to and movable along said follower guide rod, the improvement which comprises a slot within each of the upstanding portions of said rail, a pair of spaced first openings at the base of said magazine and a pair of spaced second openings at the base of said rail in registration therewith, an upwardly extending pivotally movable bifurcated support member upon said base having hooks at the upper portions thereof, each bifurcation of said support member extending through said first and second openings, a first spring member upon said support member, an additional opening at the rear of said magazine, an axially movable latching member having a base portion disposed along the inner face of the base of said magazine, said base portion partially disposed within the slots in the upstanding portions of said rail, and an offset handle portion partially disposed within said additional opening, said base portion of said latching member being provided with a pair of spaced recesses engageable with said hooks, said offset portion of said latching member being also provided with a second opening therewithin to accommodate one end of said guide rod, and coil spring means disposed between said latching member and said follower urging said latching member into latched engagement with said hooks.
